UNITED STATES PATENT OFFICE.

RICHARD M. DAVIS, OF WEST PITTSTON, PENNSYLVANIA.

AUTOMATIC CARRIAGE FOR TYPE-WRITING MACHINES.

1,261,718.

Specification of Letters Patent. Patented Apr. 2, 1918.

Application filed April 13, 1917. Serial No. 161,813.

To all whom it may concern:

Be it known that I, RICHARD M. DAVIS, a citizen of the United States, residing at West Pittston, in the county of Luzerne and State 5 of Pennsylvania, have invented new and useful Improvements in Automatic Carriages for Type-Writing Machines, of which the following is a specification.

This invention is an automatic carriage 10 for a typewriting machine.

The usual method of operating the carriage of a typewriting machine to the right side is by hand and involves the lifting of the operator's hand from the keyboard. 15 Such an operation consumes time and is not productive of continuous work, as well as involving additional labor.

The invention aims to overcome this disadvantage by providing a machine, the carriage of which is manually propelled to the left and when, after having reached a predetermined point, the carriage is automatically returned to the right or starting point. 20

To this end, the invention, broadly stated, 25 comprises an automatic carriage that is manually propelled toward the left, and after reaching a predetermined point, a stop is operated to move the pawls of the step-by-step mechanism out of engagement, thus permitting a spring, which has been wound by the progressive movement, to draw the carriage to the right hand side, the movement of one of the pawls contacting with a stationary stop member operating to prevent 30 any movement of the universal bar by the key bars, the return to the right of the carriage causing it to strike against a pivoted bumper to reduce the liability of jar and shock.

40 One practical form of the invention, and the manner of constructing and operating it, will be described and illustrated in the accompanying drawings, in which:—

Figure 1 is a top plan view with broken 45 away portions.

Fig. 2 is a rear elevation.

Fig. 3 is an end elevation with part of the side frame broken away.

Fig. 4 is a sectional view on the line 4—4 50 of Fig. 1.

Fig. 5 is a perspective view of the line spacing pawl and connecting parts.

Fig. 6 is a perspective view of the bell crank lever of the key-board operated line 55 spacer.

Fig. 7 is a detailed top plan view of the back spacing mechanism.

Fig. 8 is an enlarged view of the mechanism operating the automatic line spacer.

Fig. 9 is an enlarged view of the mechanism shown in Fig. 8 at the moment of operating. 60

Fig. 10 is a perspective view of the bar operating to disengage the pawls of the step-by-step mechanism for the free return of the 65 carriage.

Fig. 11 is a perspective view of the marginal stop bar with a removable stop in position thereon.

Fig. 12 is a sectional view of the ratchet 70 wheel, sleeve, gear and shaft.

In the preferred embodiment illustrating the invention about to be described, the usual frame is employed. This frame consists of the side members 15 and 16 that are joined 75 together at the front of the machine by means of the cross member 17. The top plate 18 is mounted upon the side members 15 and 16, to which it may be secured in any suitable manner. Mounted upon the top 18 80 and secured thereto are the carriage guide supporting members 19 and 20. These members may be secured, as shown, by the screws 21. These members 19 and 20 carry a guide rail 22, which may be of any usual type or 85 form best adapted to perform its function, and is shown as being adapted to coöperate with rollers (not shown). Positioned a suitable distance below the guide 22 is another guide 23, which may be of the same shape as 90 that of the guide 22.

Adapted to coöperate with the guides 22 and 23 there is provided a carriage, which is provided with suitable bearing portions with grooves therein to correspond with the form 95 and shape of the guides.

The carriage.

The carriage comprises end members 24 and 25, and suitably journaled therein is a 100 shaft 26. This shaft 26 is adapted to be secured to the platen 27 in any usual or customary manner. To revolve the platen 27 suitable hand wheels 28 may be employed, and positioned exteriorly of the frames 24 105 and 25. The platen 27 carries at the left hand a ratchet wheel 29 by means of which the paper is advanced a line, at a time so as to provide the proper line spacing.

At the lower left side of the side mem- 110

- ber 24 there is provided a suitable attaching point 30, to which is secured the ribbon or tape 31 employed for drawing the carriage to the right hand end of its travel. 5 This ribbon or tape may be of any suitable material, and its other end is secured to a barrel 32, in which is disposed a spring (not shown).

10 The carriage at the back end carries at its lowermost point a marginal stop bar 33, which is shown more clearly in Fig. 11. At suitable spaced points upon this bar 33, there are provided recesses 34, and to engage with these recesses 34 there are movable stop members 35, one of which is shown in position in Fig. 11.

15 Pivottally mounted at the upper end of the carriage and also between the side members 24 and 25 is a bar 36 from which are suspended the members 37 and 38, which hold at their lower ends another bar 39. This bar 39 at its left hand end also carries a lever 40. This lever 40 is provided at its outer end with a finger hold 41 and at some 20 point intermediate between the finger hold and its pivotal connection with the bar 39, there is provided a spring element 42 which is secured to it and the side member 24 of the carriage. Any usual form of connections may be employed to suitably retain the spring in its operative position. Disposed upon one side of the lever 40, which will be called the line spacing lever is a stop 25 43, which is adapted to engage with the teeth of the wheel 29 mounted upon the left hand end of the platen 27. The line spacing lever 40 is provided with a cut-away portion indicated at 44, so as to be adapted to ride over the lower guide 23 without 30 contacting therewith. The finger hold 41 is for the purpose of permitting the lever 40 to be disengaged from the wheel 29 when it is desired to insert paper and bring it into a proper line adjustment, either for 35 correction or insertion.

The line spacing mechanism.

30 The line spacing mechanism may be automatically operated by the return movement of the carriage to the right hand side of the machine, and to provide for this automatic action the marginal stop bar 33 is employed. As before described, this bar carries the stop members 35 which are removable with respect to the bar. In Fig. 8 35 one of the stops is about to engage with a pivotally mounted abutting member 45, which is provided with a projection 46 to engage with the stop 35. As shown in this 40 Fig. 8, this abutting member 45 is provided with an upstanding portion 47, that is adapted to move the bar 39, which movement is shown more fully in Fig. 9, where the projection 46 is being pushed out of the

way by the stop 35, and this upstanding 45 member 47 is contacting with the bar 39 and pushing it forward. This forward movement is communicated to the line spacing lever 40.

40 This pivotally mounted abutting member 70 is provided with a resilient element 48, which is so secured that it will maintain this member in the position shown in Fig. 8. The ends of this spring may be suitably secured in any convenient workman-like 75 manner.

45 The above description applies more particularly to the automatic line spacing mechanism. To provide for manually operating the line spacing mechanism from 80 the keyboard, a keybar 49 is provided which is substantially L-shaped, and the short limb of the L is indicated at 50. This lever is pivotally mounted, as indicated at 51. The upper end of this portion 50 is 85 bent over and carries a substantially horizontal portion 52, which terminates in a vertical upstanding member 53, having a rounded end indicated at 54. The contacting face of this upstanding member 53 is 90 adapted to contact with the bar 39 moving it forward, which then operates the line spacing lever 40. The paper then may be fed by finger pressure upon the key 55 so that the paper is fed forward or the platen 95 is turned a distance which corresponds to the width of one of the teeth of the wheel 29.

50 To maintain the line spacing bar 49 in its proper position, a spring 56 is provided, 100 one end of which is secured to the bar, as indicated at 57, while the other end is attached to a pin or other suitable support 58. This pin 58 may be secured to the side member 15 of the framework in any suitable 105 manner.

55 Thus it will be seen from the description of the two types of line spacing mechanism that one is automatically controlled upon the return of the carriage to the right hand end, while the other provides for spacing the paper manually to any desired position with reference to the platen or to a guide line. 110

Carriage propelling mechanism.

115

60 To provide for moving the carriage from the right hand side to the left hand side, a rack 59 is shown as being secured between the frames 24 and 25 of the carriage. This rack is so positioned that it will co-operate 120 with a pinion 60 which is suitably journaled in a bearing 61. This bearing may be secured to the top 18 by means of the screws 62, as shown.

65 The pinion 60 is preferably provided with 125 a barrel portion 63 so that the pinion may be secured to the shaft 64 in any suitable or workmanlike manner, and also to pro-

vide for a longitudinal adjustment of the shaft 64 so that the pinion 60 will mesh properly with the teeth of the rack 59. The other end of the shaft 64 carries a bevel gear 65 which is adapted to mesh with another bevel gear 66 positioned at substantially right angles to the gear 65.

After the pinion 60 and its barrel portion 63 have been secured to the shaft 64 so that 10 the bevel gear 65 will mesh correctly with the other bevel gear 66, the barrel portion 63 may then be secured to the shaft 64 so that the gearing will be maintained in operative alignment at all times.

15 In Fig. 12, the shaft is shown as having a slotted head 67, a bearing portion 68, a shouldered end 69, and a threaded end 70. This threaded end 70 passes into and is secured to the top 18 by means of a suitably 20 threaded hole formed in the top 18. As shown, the gear 66 is provided with a sleeve or bearing portion 71, and terminates in the ratchet wheel 72, which is provided with any desired number of teeth, the teeth in this 25 ratchet wheel 72 being spaced apart on the periphery to correspond with the lettering of the type that may be employed with this machine.

To coöperate with the teeth in this ratchet 30 wheel 72 are the pawls 73, 74, and 75. The pawl 73 is pivotally mounted with respect to the top 18, as indicated at 73', and the pawl 74 has a pivotal mounting, as indicated at 76. The pawl 73 carries at one end a pin 77, 35 which is a driving fit, so as to be movable therefrom and yet fixedly mounted therein. The element 74 is not merely a pawl but a 40 slidable member actuated from the universal bar. This pin 77 and its coöperative relation to the other parts is shown more particularly in Fig. 4.

Near the engaging end of the pawl 73, there is positioned another pin 78, which projects so that a sufficient distance to afford an 45 attaching point to the spring 79 is provided. The other end of the spring 79 is suitably secured to a pin 80 carried by the pawl 74. As shown in Fig. 1, the pawl 73 is substantially L shaped.

50 The pawl 74 is also provided with a pin 81 similar in character and which performs a somewhat similar function to the pin 77 carried by the pawl 73. The coöperative relation of this pin 81 is also shown in Fig. 4. The pawl 74 is also provided with an engaging point 82 to coöperate with the teeth of the ratchet wheel 72, and upon its opposite side, there is provided a shoulder portion 83 adapted to engage with a stop 84 when 55 the pawl 74 and the teeth 82 have been moved out of contacting relation with regard to the ratchet wheel 72. The function of this shoulder and stop will be described hereafter.

Mounted above the pawls 73 and 74 is a 65 bar provided with a long leg 85 and a short leg 86 positioned at right angles thereto and terminating in an upstanding portion 87. One side of the long leg 85 is provided with an offset portion 88, and adjacent this offset 70 portion there is formed in the leg 85 a substantially square hole 89. At suitable intervals of the longitudinal axis of this leg 85, there are formed elongated slots 90, 91 and 92. A perspective view of this bar is shown 75 more particularly in Fig. 10. The pin 77 is adapted to project upwardly through the slot 91 and the pin 81 is adapted to operate in the square hole 89.

The upstanding end 87 formed on the 80 short leg 86 of the bar is adapted to coöperate with the stops 35 carried on the marginal space bar 33.

The movement of the carriage toward the left-hand side of the machine moves one of 85 the stops 35 into a contact relation with this upturned portion 87, and, as shown in Fig. 1, the pin 77 is in contact with the right hand end of the slot 91, and the pin 81 is in contact with the right hand side of the 90 square hole 89. A continued movement to the left of the slot forces this bar to the left and actuates the pawls 73 and 74 to disengage them from any ratchet action with the ratchet wheel 72. At this time the carriage 95 is not held, and the energy stored in the spring serves to return the carriage to the right hand end. As it approaches the right hand end another marginal stop 35 is employed to move the pawls in an opposite direction, tending to force them to engage 100 with the ratchet wheel 72. At the same time, the spring 79 serves to draw the engaging ends into contact. This spring 79 exerts very little force to draw the pawls 105 together, and is used more to overcome the inertia of the moving parts.

Secured to the underside of the top 18, are two L-shaped members, indicated at 93 and 94. These are secured by means of the 110 screws 95 in any suitable way. Positioned adjacent the lower ends of these L-shaped members is a transverse shaft or axle 96, which will be secured in position as indicated by the nuts 97. As shown in Fig. 3, 115 these L-shaped members are shown as being curved downwardly and toward the front of the machine. Disposed between these members 93 and 94 is an L-shaped lever 98, which is provided at the upper end with a 120 suitable connection with the pawl 74. The connection shown is that of a screw 99, operating in a slot 100 formed in the top 18. The pawl is loosely carried on the lever 98 by means of the screw. 125

The bell-crank or L-shaped lever 98 is adapted to be pivotally mounted upon and carried by the shaft 96, which is interposed

between and carried at the lower ends of the L-shaped members 93 and 94. One end of the lever 90 has a pivotal connection indicated at 101 with the adjustable connecting link which comprises a clevis end 102, and a threaded stem 103 cooperating with an elongated nut 104. The elongated nut is suitably secured to the universal bar 105, as indicated at 106. The adjustable connection 10 formed by the parts 102, 103, and 104, permits variations in the control of the throw of the pawl 74. As shown in Fig. 3, when the space bar 106 or any of the keys and their connecting bars, one of which is shown at 107, are depressed, the universal bar tends to move upward and carry with it the connecting ends cooperatively connected with the bell crank lever 98. Through the pivotal mounting 76, the screw 99 and the slot 100 formed in the top 18, the pawl is given a forward movement, which by means of the detent 82, engages with one of the teeth of the ratchet wheel 72 and tends to rotate it. At the same time the detent will engage a tooth, and the pawl 73 will come into engagement with another tooth and prevent a backward movement of the ratchet wheel. The forward movement of the pawl 74 advances the carriage the width of one letter, after the rotary motion of the ratchet wheel produces motion in the gearing, which is operatively connected with the rack 59. After the universal bar is released, the pawl 74 is drawn backward into position for engaging with another tooth. To assist the universal bar in returning to its normal position, suitable springs 108 are employed.

In order that the key bars indicated at 40 109 may have the greatest amount of leverage, they are pivotally mounted upon the shaft 110. As shown in Fig. 1, the universal bar is substantially L-shaped, and in Figs. 2 and 3, the springs 108 are shown 45 encircling the stems 113 which are provided at one end with clevises 111. The spring 108 keeps the key bar in engagement with its clevis. The stems 113 are adapted to extend through a distance bar 114, which 50 cooperates with the side members 15 and 16. As shown, this distance bar 114 is rectangular or I-shaped, so as to provide a large bearing surface for one end of each of the springs 108, when they are put under compression by a downward pressure, at which 55 time the clevises contact with them.

As the carriage is moved progressively in a step-by-step manner toward the left hand side of the machine, the spring contained in 60 the spring barrel 32 has energy stored therein by means of the tape 31, which is adapted to rotate the barrel. This forward movement of the carriage is accomplished manually, which is in contradistinction to the

usual method of advancing the carriage, 65 and when the carriage has reached the limit of its travel to the left as determined by the marginal stop, the pawls 73 and 74 are automatically disengaged, and the carriage is thus permitted to have a free return 70 through the spring.

If at any time it is desired to return the carriage to the right either a short distance, or to the limit as indicated by the marginal stop, a carriage release key 115 is provided 75 in the bank of keys of the keyboard. This key 115 is connected to a suitable L-shaped lever having the legs 116 and 117. This L-shaped lever is provided with a pivotal mounting, indicated at 51. The upper end 80 of the leg 117 is provided with a hole 119, which is adapted to coöperate with a pin or other suitable bearing 120. This affords a connection with the depending portion 121 of another L- or bell-crank lever having the 85 members 122 and 123. This bell-crank lever has a pivotal mounting, as indicated at 124. Adjacent the outer end of the member 123, a pivotal connection 125 is provided so as to coöperate with the shifting bar 126. This 90 bar 126 is provided with suitable slots 149, 150, 151 and 152, which are so positioned as to coöperate with the pins 77 and 81 carried by the pawls 73 and 74.

When the key 115 is depressed, its motion 95 is communicated through the two L-shaped or bell-crank levers, and by means of the pivotal connection indicated at 125, this bar 126 is pulled toward the left, which movement separates the detents of the pawls 73 100 and 74 and permits the carriage to move to the right. The movement to the right may be arrested at any point, and is dependent upon the length of time the key 115 is depressed. If depressed continuously, or that 105 is, for a length of time, the carriage will move to the extreme right hand end, but if depressed for an interval, it will move for a distance corresponding to that time.

In this shifting bar 126, there are also 110 slots formed which are adapted to coöperate with the retaining screws having a head 127 and a threaded shank portion 128. The threaded portion 128 is adapted to coöperate with a threaded hole formed in the top 18 115 of the machine. The relation of the bar 126 to the other operating parts and the screws is shown more particularly in Fig. 4, while in Fig. 1 there is shown a view of the interposed bell-crank lever which coöperates with 120 the keybars.

Thus, by means of the key 115, and its coöperating parts, a controlled return of the carriage release is provided, and being situated in the bank of keys the carriage may be 125 returned without lifting the hands. To maintain the keybar 116 in its normal operative position, a spring 130 is employed.

One end of this spring is secured to a pin 58, while the other end is attached to the key-bar.

When the pawls 73 and 74 have been disengaged from contact with the ratchet wheel 72, the pawl 74 in its outward movement contacts with the stop 84 by means of the shoulder 83. The position of this stop and the angle formed by the shoulder is such that 5 the pawl is forced directly against this stop and a further movement is prevented. When the pawl is held in this position against the stop, the universal bar is locked and the movement of the keys may be suppressed 10 during the return of the carriage to the right hand end of the machine. This prevents writing during the shifting movement of the carriage. When the carriage arrives at the right hand end, the pawls are automatically brought into engagement with the 15 ratchet wheel and the pawl 74 is disengaged from contact with the stop 84, at which time writing may proceed. This is an advantage because when one is writing near the right 20 hand end of the paper, the carriage might be returned in the middle of a word, and if no provision were made, the keys would be striking the platen and the paper during the shifting movement. This would be especially 25 true if notice had not been taken of the alarm signal for the left hand travel of the carriage.

The back spacing mechanism.

35 The back spacing mechanism is controlled from the right hand side of the machine by means of the key 129, which is secured to the bell crank lever having the members 131 and 132, and is mounted for pivotal movement, 40 as indicated at 118. The upper end of the upstanding member 132 is provided at its upper end with an open-ended slot 133, which is adapted to coöperate with the pin 134. This pin 134 is mounted in a down- 45 wardly bent portion 135 formed in the member 136 forming a part of the bell crank lever. The other member of this bell crank lever is indicated at 137. To provide pivotal action of this bell crank lever a suitable 50 pivot 138 is employed.

In the outer end of the member 137 there is provided means for a pivotal connection indicated at 139 with the actuating bar 140. Disposed intermediate of the ends of this 55 actuating bar are slots 141 and 142, and adjacent the outer end of the bar there is formed another slot 143. Adjacent the slot 143 there is provided a substantially square hole 144, and the bar 140 is provided with an 60 off-set projection 145.

Disposed between the slot 142 and the hole 144 is a detent or pawl 146, which is pivotally mounted on the bar as indicated at 147. The outer end of the pawl 146 is pro-

vided with a tooth engaging portion 75, 65 which adapts it to coöperate with the teeth of the ratchet wheel 72. The pawl 74 carries a pin 80 which forms a point of connection for its spring 79. In Fig. 7, the pawl 146 is shown as having wedge-shaped sides, the 70 widest part being substantially centrally of the pawl.

When the actuating bar 140 is moved toward the left, the pawls 73 and 74 are separated, and at the same time the detent portion of the pawl 146 is brought into engagement with one of the teeth of the ratchet wheel 72. Just at the time of coming into contact with the ratchet wheel 72, the wheel is rotated backward and is caught by its detent portion 75. When the pawl 146 is released the pawl 73 will then engage with a tooth, and firmly holds it against any further backward movement. This corresponds to the width of one letter by permitting the 80 ratchet wheel 72 to move backward one tooth. To maintain the several parts of the back spacing mechanism in a normal position, a suitable spring 153 is employed. One end of the spring 153 is secured to a pin or projection 90 154, and the other end is connected in any suitable manner to the keybar 131.

When it is desired to retract or move the carriage a space at a time to the right, the key 129 is operated and by means of the connections of the L- or bell crank lever described, the actuating bar 140 is moved to the left. The pins 77 and 81 carried by the main escapement pawls 73 and 74 project through the slots 142 and 144, and through the slots 100 141 and 143 to engage with the stop members having the threaded stems 128. The correlation of the several parts is shown more clearly in Fig. 4. These stops serve to limit the motion of the actuating bar 140 so that 105 the carriage is released only one space at a time when in coöperative action with the pawls 73 and 74, which come into action at the moment of the releasing of the pawl 146.

The shock absorbing mechanism.

Mounted at the right hand side of the frame and upon the side member 16, there is a mechanism to reduce the shock and jar incident to the return of the carriage to 115 such right hand side, the carriage being brought over and returned by means of the spring. The shock absorbing mechanism is mounted so as to retard the carriage during the last portion of its travel. As shown in 120 Fig. 2, this shock absorbing mechanism comprises a lever having the members 155 and 156 angularly displaced with relation to each other. This lever is pivotally mounted upon a shaft 157, which is carried by a support 158. This support 158 may be secured to the side member 16 of the frame by means of the bolt 159. If desired, this supporting 125

member may be formed of two parts or in any other approved manner, the means being shown for illustrative purposes only.

Projecting from the member 155, there is a curved portion 160, which has encircling it a spring 161. The free end of this curved member 160 may project through a suitable slot or opening in the side member 16 of the frame, and as shown in Fig. 2 the spring is interposed between the side member 16 and the member 155 of the lever. The other member 156 of this lever is provided adjacent its upper end with a suitable opening to provide for a pivotal action of the pawl 162, the pivotal connection being indicated at 163.

Formed upon the frame near the top, a suitable boss 164 is provided and the member 156 of the lever is so formed that it provides a hammer face which is adapted to carry felt, rubber, or other suitable noise preventing material 165. As shown, the pawl 162 is provided with two ends which are curved in substantially the same direction. The upper end being free, permits the side member 25 of the carriage to ride over the same to the left hand side of the machine. Upon its opposite side an engaging face is provided, which upon the return of the carriage will engage the opposite side of the side frame 25. To prevent the pawl from being rotated when the carriage is approaching the right hand side, a stop 166 is provided to limit the movement of the pawl 162 in one direction.

To maintain the pawl in an operative position, a suitable spring 167 is employed, one end of which is attached to the pawl, as indicated at 168, while the other end is attached to the lever on the member 156, as indicated at 169.

The return of the carriage to the right being effected with considerable force due to the expenditure of the energy by the spring, the right hand member 25 of the carriage engages with a suitable surface formed on the pawl 162. The pawl being pivotally mounted, as indicated at 163, its opposite end is forced into engagement with the pin 166. The continued movement to the right then causes the pawl 162 to move the two members 155 and 156 of the lever, tending to compress the spring 161 carried on the curved member 160. The continued movement of the carriage to the right compresses the spring still farther, thereby slowing up its action as it reaches the limit of its travel and at the same time the pawl 162 rides under the frame 25 and returns to its normal operating and engaging position by means of the spring 167. Thus any shock or jar which would be occasioned by the carriage coming to a sudden stop by means of the spring action on its return is obviated, and the car-

riage comes to rest with very little jar simulating the movement by hand although in this instance being automatic.

The bell signal.

Disposed upon the carriage between the end frames 24 and 25, there is a back plate 170, which may be secured to the carriage end frames in any convenient manner. Secured to this plate 170 through an appropriate connection indicated at 171 is a pawl 172, the upper end of the pawl being adapted to engage with a stop member 173 to limit its movement in one direction. The lower portion of the pawl extends below the pivot a sufficient distance to engage with a spring element 174. This spring element may be secured to the side frame of the machine 15 as indicated at 175. As shown in Figs. 2 and 3, this spring element projects slightly above the top 18 of the frame, and at some point intermediate of its ends there is secured a tapper or hammer 175^a, that is adapted to contact with the bell 176. The bell 176 may be secured to the machine in any usual or customary manner, one means being shown by the stud 177. To hold the pawl 172 in position for operative engagement with the spring element 174, a suitable spring 178 is employed, one end of which is secured to the pawl and the other to a stud 95 indicated at 179.

As the carriage moves toward the left side of the machine, the lower end of the pawl 172 engages with the spring element 174, forcing it outward until the bending of the element is sufficient to cause it to pass underneath the lowermost end of the pawl 172, when it will fly back with considerable force and cause a signal to be sounded, showing that the carriage is approaching the end of its travel.

The carriage tension.

The carriage tension mechanism comprises a barrel 32, in which may be mounted a suitable spring, one end of this spring being connected to the shaft 180, and is adapted to coöperate with the ratchet wheel 181 having an engaging pawl or detent 182 pivotally mounted as indicated at 183.

To wind up the spring or to release it, the handles 184 and 185 carried by the ratchet wheel 181 and the pawl 182, respectively, may be employed.

What is claimed is:—

1. In a device of the class described, a universal bar, a slidably mounted member carrying a tooth, means for moving said member from the bar, a ratchet wheel, a gear wheel rotating therewith, a carriage, means for operating the carriage by the rotation of said gear wheel, a holding pawl engaging the ratchet wheel, and resilient means connecting said pawl and slidable member.

2. In a device of the class described, a universal bar, a ratchet wheel, a member moving at an angle therewith and including a tooth engaging the ratchet wheel, 5 means for moving said member from the universal bar, a gear wheel movable with the ratchet wheel, a carriage means for moving the carriage from the gear wheel upon the movement of said universal bar, 10 a holding pawl engaging the ratchet wheel, resilient means connecting said pawl with the member operated by the universal bar, and means for releasing said holding pawl and moving said member and the tooth carried thereby out of the path of movement 15 of the ratchet wheel.
3. In a device of the class described, a carriage, means for positively moving the carriage along a printing line by the operation 20 of the keys of a typewriter, said means including a plurality of gear wheels, a ratchet wheel moving with one of said gear wheels, a member carrying a tooth engaging the ratchet wheel and movable at 25 an angle to the axis of said wheel, means for operating said member upon the movement of the keys, a holding pawl engaging the ratchet wheel, and means for throwing said holding pawl and said tooth first mentioned out of engagement with the ratchet 30 wheel.
4. In a device of the class described, a carriage, means for positively moving the carriage along a printing line by the operation 35 of the keys of a typewriter, said means including a plurality of gear wheels, a ratchet wheel moving with one of said gear wheels, a member carrying a tooth engaging the ratchet wheel and movable at an 40 angle with the axis of said wheel, means for operating said member upon the movement of the keys, a holding pawl engaging the ratchet wheel, and means for throwing said holding pawl and said tooth first mentioned out of engagement with the ratchet 45 wheel, said means last named including automatically operated and manually operated devices.
5. In a device of the class described, a carriage, means for advancing the carriage along a printing line, and including a 50
- ratchet wheel, key operated means for operating the ratchet wheel and moving the carriage in one direction, spring controlled means for moving the carriage in the opposite direction, a holding pawl, and means automatically operated for disengaging the holding pawl and the actuating means simultaneously, said actuating means and holding pawl moving into engagement with the ratchet wheel from opposite directions, 55 and a spring connecting the pawl and a portion of the holding means.
6. In a device of the class described, a universal bar, a carriage, a ratchet wheel, 60 means operated by said ratchet wheel for positively moving the carriage forwardly along a printing line, means for actuating the ratchet wheel, a plate member having a limited longitudinal movement in the direction of the movement of the carriage, 65 means for actuating said plate member when the carriage reaches a predetermined position, the actuating means including a member slidably mounted and operating at 70 an angle with said plate member, means on the slideable member engaging the ratchet wheel, and means for throwing out of action a portion of the actuating means by the throwing out of action of said plate member. 75
7. In a device of the class described, a universal bar, a ratchet wheel, a carriage, means for advancing the carriage along a printing line by the movement of the ratchet wheel and means for actuating the ratchet wheel from the universal bar, 80 said means including a slideable plate movable at an angle with the direction of the travel of the carriage, means thereon engaging the ratchet wheel, a plate having a limited 85 movement longitudinally with reference to the movement of the carriage, and at an angle with said slideable member, a holding pawl engaging the ratchet wheel and means for throwing said holding pawl and engaging means first mentioned out of contact with the ratchet wheel by the operation of said longitudinally movable plate member 90 when the carriage reaches a predetermined position. 95

In testimony whereof I affix my signature.

RICHARD M. DAVIS.
